CUFF CREAMING AND BUTTONHOLE ALIGNING DEVICE

Filed June 19, 1930

UNITED STATES PATENT OFFICE

JAMES W. STEELE, OF DALLAS, TEXAS

CUFF CREAMING AND BUTTONHOLE ALIGNING DEVICE

Application filed June 19, 1930. Serial No. 462,183.

This invention relates to laundry appliances for either domestic or commercial use and it has particular reference to cuff creaming devices and the principal object of the invention resides in an apparatus for both creasing the cuff and aligning the buttonholes in a folded cuff.

Another object of the invention resides in its peculiar adaptability for use in connection with conventional shirt folding devices, especially those employed for doing up these garments in laundries, the invention occupying but little space and consequently does not interfere with the operator employed to fold the garments preparatory to delivery to the customer.

Still another object of the invention resides in a device of the character mentioned having facilities by which a cuff may be folded a number of times, yet without deviation from the crease made by the first folding thereof, which is effective in maintaining the wear at one point as well as any stains along the folded edge of the cuff.

With the foregoing objects as paramount, the invention has particular reference to its salient features of construction, purpose and arrangement of parts to become manifest as the description proceeds, taken in connection with the accompanying drawings, wherein:

Figure 1 is a perspective view of a cuff creaming and buttonhole aligning device constructed according to the present invention.

Figure 2 is a side elevational view, with one portion broken away to illustrate the tensioning means to allow for adjustability of one of the buttonhole aligning studs.

Figure 3 is a view on lines 3—3 of Figure 2.

Figure 4 is a plan view of the invention illustrating the manner in which a cuff is applied thereto for aligning of the buttonhole, and

Figure 5 is an end elevational showing a layer of padding to enable an iron to be passed over the cuff for creasing the same.

Conventionally, after a shirt or similar garment is ironed, the cuffs of the sleeves are folded and creased by hand and in the case of the folded cuff, wherein there are four buttonholes, it is difficult to align these holes

to agree with the fold, by hand. When this is done by hand there is always the possibility of dis-alignment each time the shirt is laundered and in which event the crease is in a different position and when worn edges will assume different positions, resulting in non-uniform wear at the folding point of the cuff. This is equally true of any stains on the folded portion which cannot be removed by laundering and it is desirable that any such stains and wear be along the folded portion of the cuff.

The present invention therefore contemplates the provision of a device which may be secured at some convenient point adjacent the operator's table and preferably mounted upon the folding board in order that the person employed to fold the shirts may have ready access to the device.

Accordingly, the invention is comprised of a substantially rectangular hollow body 1, composed of any suitable material, either wood or metal, but preferably aluminum. The body 1 has a rectangular extended portion 2 in which there is a slot *a* and an aperture *b* through which is passed bolts *c* to mount the same.

Adjacent one edge of the body there is a fixed stud 3 and a longitudinally movable stud 4. This latter stud is arranged to be so moved in order that it will accommodate cuffs 5 in which the distance between the buttonholes 6 vary, as shown in Figure 4. A non-frictional member 8 reposes within the slot 7 and provides a guide for the said stud 4 when the latter is moved lengthwise of the slot 7. The non-frictional element, which may be of metal or fiber material is affixed through the medium of the threaded pin 9, integral with the said stud 4 to an L-shaped member 10, which member is yieldably connected, through the medium of a spring 11 to one end of the body 1 through the medium of a small bolt and hook 12. The companion stud 3 is affixed to the body 1 by means of a nut 13 threaded upon an integral pin 14.

It is obvious from the foregoing description that when the buttonholes 6 on either side of the cuff 5 are placed upon the studs 3 and 4, in the manner shown in Figure 4, the

folded portion may be turned to overlap that portion of the cuff next adjacent the sleeve 15 and the buttonholes 6 in said folded portion are likewise inserted over the studs 3 and 4 to insure positive aligning of the four buttonholes. When such aligning is obtained, a true fold at *d* is insured and it is sufficient in most cases to move the finger along the fold to crease the same. However, in some cases, it is desirable to further crease the fold by running the smoothing iron thereover and in which case there is provided a layer of padding material 16 which overreaches the operative surface of the device.

Manifestly, the construction shown is capable of considerable modification and such modification as is considered within the scope and meaning of the appended claims is also considered within the spirit and intent of the invention.

What is claimed is:

1. A folding and buttonhole aligning device for cuffs including a rectangular hollow body having a flange provided with an aperture at one end and a slotted opening at the opposite end, a flattened stud removably mounted at one end of said body adjacent said flange, a similar stud mounted in a slot at the opposite end of said body in alignment with said first stud, means for retaining said stud in said slot for sliding movement and means within said body to yieldingly return said stud to normal position when the latter is moved in said slot.

2. A folding and aligning device for shirt cuffs including a hollow rectangular body having a mounting flange integral therewith provided with a screw receiving aperture at one end and a slot at the opposite end a stud projecting upwardly from the surface of said body at one end and adjacent its edge, a second stud mounted in a slot at the opposite end and adjacent the edge of said body and having means for retaining the same for sliding movement in said slot and means below said second stud for yieldingly connecting said stud to said body to cause the same to return to normal position when moved in said slot.

50 In testimony whereof I affix my signature.
JAMES W. STEELE.
